(57) **CLAIM**

The ornamental design for a heel plate for a wheel weight removal tool, as shown and described.

DESCRIPTION

FIG. 1 is a perspective view of a heel plate for a wheel weight removal tool showing the new design;

FIG. 2 is a top plan view thereof from FIG. 1.

FIG. 3 is a front plan view thereof from FIG. 1.

FIG. 4 is a first side plan view thereof from FIG. 1;

FIG. 5 is a back plan view thereof from FIG. 1.

FIG. 6 is a second side plan view thereof from FIG. 1; and, FIG. 7 is a bottom plan view thereof from FIG. 1.
